Primary Examiner — Shawn T Gingrich*(74) Attorney, Agent, or Firm* — Andrus Intellectual Property Law, LLP(57) **CLAIM**

We claim the ornamental design for a plug, as shown and described.

DESCRIPTION

FIG. 1 is a rear perspective view of a plug showing our new design.

FIG. 2 is a front perspective view of the plug of FIG. 1.

FIG. 3 is a rear view of the plug of FIG. 1.

FIG. 4 is a front view of the plug of FIG. 1.

FIG. 5 is a first side view of the plug of FIG. 1.

FIG. 6 is a second side view of the plug of FIG. 1.

FIG. 7 is a top view of the plug of FIG. 1; and,

FIG. 8 is a bottom view of the plug of FIG. 1.

Any portion of the connector assembly shown in broken lines is included for the purpose of illustrating environment and forms no part of the claimed design.
